CLAIM

The ornamental design for a camera mount for a person's arm, as shown and described.

DESCRIPTION

FIG. 1 is a front perspective view of a camera mount for a person's arm showing our new design;

FIG. 2 is a right side elevational view, the undisclosed left side being a mirror image thereof;

FIG. 3 is a top view of our design;

FIG. 4 is a bottom view of our design;

FIG. 5 is a front elevational view of our design; and,

FIG. 6 is a rear elevational view of our design.

The features shown in broken lines in FIG. 1 are shown for illustrative purpose only and form no part of the claimed design.
